United States Patent Office

Des. 218,723

Patented Sept. 15, 1970

218,723

VEGETABLE POD OPENER

Charles L. Westbrook, 715 Washington Ave.,
Ayden, N.C. 28513

Filed Jan. 9, 1969, Ser. No. 15,277

Term of patent 14 years

Int. Cl. D7—99

U.S. Cl. D89—1

Fig. 1.

Fig. 2.

Fig. 3.

Fig. 4.

Fig. 5.

FIG. 1 is an exploded perspective view showing my new design opener;

FIG. 2 is a plan view;

FIG. 3 is a side elevation;

FIG. 4 is a front view; and

FIG. 5 is a bottom view.

The dominant features of my invention are in solid lines.

I claim:

The ornamental design for a vegetable pod opener, as shown.
